UNITED STATES PATENT OFFICE.

LEO MOTT VAN WAGNER AND JOHN A. DUFFY, OF FAR ROCKAWAY, NEW YORK.

DESIGN FOR A CUSHION SOLE-PAD FOR BOOTS AND SHOES.

55,343.

Specification for Design.

Patented May 25, 1920.

Application filed August 11, 1919. Serial No. 316,879. Term of patent 3½ years.

To all whom it may concern:

Be it known that we, LEO M. VAN WAGNER and JOHN A. DUFFY, citizens of the United States, residing at Far Rockaway, Long Island, in the county of Queens and State of New York, have invented a new, original, and ornamental Design for Cushion Sole-Pads for Boots and Shoes, of which the following is a specification, reference being had to the accompanying drawing, forming part thereof.

Figure 1 is a plan view showing the sole pad, the shoe sole being indicated in dotted lines.

Fig. 2 is an edge view of the same.

We claim;

The ornamental design for a cushion sole-pad for boots and shoes, as shown.

LEO MOTT VAN WAGNER.
JOHN A. DUFFY.
